No. 673,141.

G. E. RUTLEDGE.
KNITTING MACHINE.

Patented Apr. 30, 1901.

(Application filed Dec. 16, 1899.)

(No Model.)

UNITED STATES PATENT OFFICE.

GEORGE E. RUTLEDGE, OF CHICAGO, ILLINOIS, ASSIGNOR TO THE GEORGE D. WHITCOMB COMPANY, OF SAME PLACE.

KNITTING-MACHINE.

SPECIFICATION forming part of Letters Patent No. 673,141, dated April 30, 1901.

Application filed December 16, 1899. Serial No. 740,492. (No model.)

To all whom it may concern:

Be it known that I, GEORGE E. RUTLEDGE, a citizen of the United States, and a resident of Chicago, county of Cook, and State of Illinois, have invented certain new and useful Improvements in Knitting-Machines, of which the following is a specification, and which are illustrated in the accompanying drawings, forming a part thereof.

10 This invention relates to what are known as "straight-knitting" machines, in which are employed two banks of needles arranged upon inclined plates, which are spaced apart to form a slot through which the fabric passes as 15 formed, and the particular feature of the machine involved is the mechanism for casting off the stitches as formed upon the needles.

The invention consists in providing the machine with removable fixed casting-off jacks 20 positioned alternately with the needles, as fully hereinafter described and as illustrated in the accompanying drawings, in which—

Figure 1 is a detail transverse vertical section of a knitting-machine of the type named. 25 Fig. 2 is a detail plan view of the same. Fig. 3 is a detail plan of a portion of the machine. Fig. 4 shows details in vertical section and in plan of parts of the machine. Fig. 5 shows one form of the casting-off jacks in side elevation and in plan, and Fig. 6 is a detail inverted plan of the needle-plate.

At 9 are shown supporting-rails for the needle-plates 10 10, and at 11 11 are shown upper rails superimposed upon the needle- 35 plates and carrying guide-rails 12, upon which certain reciprocating parts of the machine (not shown) ride. For the purposes of this case the parts 11 and 12 may be treated as one. The upper surfaces of the needle-plates 40 10 are grooved to receive the needles X, and their upper edges are recessed for the accommodation of the jacks, as hereinafter more fully described, the grooves and recesses of the needle-plates being arranged alternately, 45 so that the upper edge of each of the needle-plates is provided with a plurality of forwardly-projecting fingers 13, which are in line with the grooves and serve as supports for the needles. The upper edges of the rails

11 11 are recessed to correspond with the recesses of the needle-plates, so as to form forwardly-projecting tongues 14, each of which overhangs one of the fingers 13.

Each of the jacks 15 is a thin metal plate, approximately oblong rectangular in general 55 contour, adapted to fit within the recesses in the upper edges of the needle-plates 10 10 and rails 11 11, and is provided with an aperture 16, registering with a corresponding aperture in the tongues 14, for the reception of 60 a rod 17, so that when the jacks are all in proper position the rod may be thrust in from the end of the needle-plate, so as to pass through all of the jacks and tongues and secure them in position. The lower edge 65 of the forward portion of each jack rests upon the needle-plate 10 at the base of its recess and upon the top of the rail 9, and the lower portion of its front edge is beveled to correspond with the inner face of the rail 9. 70 The upper portion of the front edge of the jack is beveled backwardly, so that its line is more nearly perpendicular to the direction of movement of the needle. The jacks are supported at their upper rearward corners 75 by a bar 18, interposed between them and the rail 12. This bar 18 has a wedge action for the purpose of securely locking the jacks in position, the face of the rail 12 and the rearward edge of the jack 15, between which the 80 rod is interposed, being slightly divergent and the contacting faces of the bar being correspondingly alined.

The height of the jacks is such that their upper forward corners are just cleared by the 85 needle advancing from the opposite side of the machine. The function of the jacks is to strip the stitch from the needle as it recedes. This function has heretofore been performed by an integral part of the needle-plate, and as a result any injury to such part would throw the entire machine out of service for a considerable time and might cause the loss of the entire plate. By providing 90 separate jacks to perform this function injury to any of them is quickly repaired by withdrawing the rod 17, removing the disabled jack, and substituting a new one, and

then again inserting the securing-rod, an operation accomplished in the space of a very few minutes.

I claim as my invention—

- 5 1. In a knitting-machine, in combination, a grooved needle-plate having its edge recessed alternately with the grooves, a frame-plate above the needle-plate and having its edge recessed in register with the needle-plate 10 recesses to form forwardly-projecting tongues, such tongues being transversely apertured in line, fixed casting-off jacks fitting within the recesses of both plates, and being apertured in register with the apertures of the frame-plate tongues, and a removable rod entering 15 the apertures of the tongues and jacks, substantially as described.
2. In a knitting-machine, in combination, a needle-plate, fixed casting-off jacks removably secured at the forward edge of the plate, and a wedge-bar fitted between the rearward 20

edge of the jacks and a fixed part of the machine.

3. In a knitting-machine, in combination, a grooved needle-plate having its edge recessed alternately with the grooves, a frame-plate above the needle-plate and having its edge recessed in register with the needle-plate 25 recesses to form forwardly-projecting tongues, such tongues being transversely apertured in line, fixed casting-off jacks fitting within the recesses of both plates, and being apertured in register with the apertures of the frame-plate tongues, a rod entering the 30 apertures of the tongues and jacks, and a wedge-bar interposed between the rear edges of the jacks and a fixed part of the machine, 35 substantially as described.

GEORGE E. RUTLEDGE.
